CASTING DEVICE

Crawford Park, Youngstown, Ohio

Application February 24, 1938, Serial No. 192,208

2 Claims. (Cl. 22-2)

This invention relates to a device for casting stereotype plates.

The principal object of this invention is the provision of a casting device having its casting box so designed that the various parts of the box lock together automatically when the box is raised to casting position.

A further object of this invention is the provision of a casting device having its melting pot in such relation to the casting box that the metal may be poured without the necessity for moving the melting pot or handling it in any way.

A further object of this invention is the provision of a casting device so arranged as to prevent actual spilling or splashing of the molten metal, thus providing an unusually safe device.

A further object of this invention is the provision of bars or mat bearers in the casting box, so designed as to grip the matrix and straw board backing firmly, thus insuring positive location of the bars or mat bearers.

A still further object of this invention is the provision of a casting box locking means arranged so that the thickness of the stereotype plate (usually called the "height") may be varied.

The device shown and described herein constitutes an improvement over that shown in my Patent No. 2,070,975, issued Feb. 16, 1937.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a side elevation of the device with parts broken away.

Figure 2 is a top plan view of a portion of the device shown by line 2-2 in Figure 1.

Figure 3 is an enlarged detail showing the means for locking the platens in position.

Figure 4 is a cross section taken on line 4-4 of Figure 2.

By referring to the drawing it will be seen that there is provided a stand 1. Positioned on this stand 1 there is a circular base member 2 which supports a melting pot 3. This melting pot 3 is provided with a heating element 4, preferably electric, and also with a pouring spout 5. Posi-

tioned within the melting pot is a circular displacement member 6, the circumference of which is slightly less than the circumference of the melting pot 3, so that it may be forced downwardly by means of a handle 7 into the melting pot 3 as to cause the stereotype metal 8 to flow out of the spout 5. Positioned around the lower portion of the circular base member 2 there are provided shields 9. Positioned between these shields 9 there is a casting box comprising a top platen 10 and a bottom platen 11. The top platen 10 is held in position by stationary threaded pivots 12, and the bottom platen 11 is slidably positioned on a roller 13, having offset pins 14 formed as a part thereof, and designed to operate in conjunction with bolt ends 15 of counter sunk bolts 20 to provide the necessary adjustment when the "height" of the casting is varied the roller 13 being pivoted to and positioned between a pair of shields 9.

Positioned on the bottom platen 11 there are a plurality of catches 16, each of which comprises an upright having two tapered arms extending therefrom at right angles. A plurality of slotted openings 17 are provided in the top platen 10 to receive some of the catches 16, the remainder of the catches 16 being intended to slide over the edge 18 of the top platen 10 as shown in Figure 3.

By referring to Figure 2 it will be seen that three bars or mat bearers 19 are positioned on the bottom platen 11. The horizontal one of these bars is bolted to the bottom platen 11 by means of counter sunk bolts 20. The other two of these bars have raised edges 21 as shown in detail in Figure 4. These raised edges are provided to grip the matrix and the strawboard 22 so as to hold these two bars securely when the box is locked in casting position as they are not otherwise attached.

It will be seen that the casting box of this device is so designed that the matrix is placed in the proper position therein on the platen 11, the top platen 10 lowered, and the casting box is then moved to a vertical position, during which action the top and bottom platens automatically lock together, thus holding the matrix and bars or mat bearers in correct position at the time the casting is poured. By referring again to Figure 3 it will be seen that a section of the platen 10 is shown in phantom at 10-A, this being the proper position for a shallow casting. It is obvious that the bars or mat bearers used for a shallow casting are necessarily thinner and of substantially less height than the bars or mat

- bearers 19. A simple spring catch 23 is provided on one of the shields 9 and is designed to hold the casting box in an upright position. This catch 23 is also used to hold only the top platen 10 in an upright position where it will form a shield when the casting box is open, as shown in Figure 2. This catch 23 comprises a tapered piece of spring steel attached to the shield 9 along one edge, thus requiring its manual operation in order to release the casting box from pouring position, or to release the top platen 10 from its shield position.

It will be seen that the casting box, when released and lowered, will automatically become unlocked due to the resulting sliding action of the platens in relation to each other caused by the engagement of the bolt ends 15 with the pins 14 of the roller 13.

It will be seen that the "height" of the casting may be changed by reversing the position of the roller 13, thus moving it closer to the threaded pivots 12, and causing a difference in the space between the platens.

What I claim is:

- 25 1. A casting box for casting stereotype plates, said casting box comprising a pair of platens, one of which is pivoted to and positioned between a pair of shields, and the other slidably

positioned on a roller which is eccentrically pivoted to and positioned between a pair of shields, catch means for locking said platens together when they are raised vertically, said catch means comprising a plurality of uprights, tapered arms on said uprights adapted to engage the platen opposite, either over the edges of the said platen or through suitable slots in the platen, bars positioned between the said platens to form a suitable casting frame, counter sunk bolts in one of said bars, adapted to hold it securely to the said platen, eccentrically positioned pins formed in the said roller adapted to engage the said counter sunk bolt ends to hold the said platen in position.

2. A casting box for casting stereotype plates, said casting box comprising a pair of platens, one of which is pivoted to and positioned between a pair of shields and the other slidably maintained on a roller which is eccentrically pivoted to and positioned between the said pair of shields, catch means for locking the said platens together when they are moved to vertical position, said catch means comprise a plurality of uprights, tapered arms on each upright adapted to engage the platen opposite, either over the edges of the said platen or through suitable slots in the said platen.
